METHOD AND APPARATUS FOR APPLYING
METAL COATINGSPurling A. Bleakley, Hollywood, Calif., assignor,
by mesne assignments, to The Gillord Corpora-
tion, a corporation of Delaware

Application February 7, 1933, Serial No. 655,610

26 Claims. (Cl. 91—12.2)

This invention has to do in a general way with the art of surfacing articles or objects, such as the interior of cylindrical objects, and is more particularly related to a method and apparatus for applying a hard metal surface having a high co-efficient of friction and a consequent high gripping action to the wearing surface of articles such as brake drums or the like, although the invention is not limited to that use.

10 The method and apparatus contemplated by this invention are especially adapted for use in reclaiming scored or worn brake drums, but they may, also, in view of the very desirable characteristics produced in the wearing surface, find 15 useful application in the production of new brake drums as well as for various surfacing purposes.

The surface referred to above in the method contemplated by this invention, is obtained by spraying the wearing surface of the drums with 20 hot metal in a manner such that the deposited coating comprises a porous mat which is formed of overlapping layers of metal particles bonded to each other and to the drum. By laying the sprayed metal onto the wearing surface in the 25 overlapping manner just described, the surface formed can be ground so that the finished article is perfectly symmetrical and can be used indefinitely without danger of chipping or flaking.

It is a well known fact that metal, such as steel 30 for example, when it is deposited by the so-called spray method is not only porous but is increased in hardness over the original metal. Also in view of its more or less porous qualities it has a much higher co-efficient of friction and gripping 35 action than the original metal. With this in mind, my invention also contemplates as an article of manufacture, a brake drum, the wearing surface of which has a coating of the type just described.

40 It is one object of this invention to produce a method for applying a coating, of the type referred to above, to the interior of a brake drum or the like. This method consists in a general way of directing a metal spray against the wearing 45 surface of the brake drum while rotating the brake drum and at the same time effecting relative movement, in a direction parallel to the axis of rotation of the drum, between the drum and the spray.

50 The means for producing the metal spray may be any conventional type of so-called spray gun whereby a metal wire or rod is melted by means of an oxyacetylene flame or the like and the molten metal as it forms is torn from the rod, 55 disseminated, and deposited on the surface being

sprayed by means of a high velocity blast of compressed air. However, it is a primary object of this invention to produce a machine whereby a gun of the class described may be used to lay a uniformly matted coating which is made up of 5 overlapping layers of the type referred to above.

It is a further object of this invention to produce a machine of the class described wherein a plurality of drums or other articles may be simultaneously coated in the manner referred to, 10 In this connection, it is an important feature of the machine contemplated by this invention that surfaced drums may be replaced with unsurfaced drums during the surfacing of another set of drums. 15

The machine contemplated by this invention consists in a general way of a table which is rotatably supported upon suitable supporting means and is associated with a table clutch operated by a main drive shaft for the purpose of 20 effecting intermittent rotation of the table at predetermined intervals. An upright guide member mounted upon a suitable support is situated adjacent the table and this guide member carries a traveling arm which has a projecting end 25 situated above the table for supporting, in adjustable relation with respect to the table, one or more spray guns. The table is provided with a plurality of work supporting members which, in the example given, will carry mandrels supporting the brake drums, and latch means are provided for engaging suitably positioned stops on the table to lock and hold the same against 30 rotation in a position where the drums are exposed to the action of the spray. 35

Means are provided for rotating the drums from the main drive shaft at such times as the table is held stationary, and means in the form of an upright feed screw, associated with a traveling member, is provided for the purpose of 40 moving the supporting arm and the spray gun downwardly toward the drums and upwardly away from the drums to apply the overlapping layers of matted metal to the interior surface 45 of the rotating drums. The down and up movement of the traveling member on the feed screw, which is driven from the main drive shaft, is effected by means of a clutch mechanism on the main drive shaft and a trip mechanism actuated by the traveling member. 50

It is a further object of this invention to provide a machine of the class described with a trip mechanism which is actuated to reverse the rotation of the feed screw when the arm reaches 55

its lowermost position without disturbing in any way the table or the table clutch.

It is a still further object of this invention to form the trip mechanism so that the feed screw clutch is thrown into neutral when the arm reaches its uppermost position and which at the same time includes a mechanism for releasing the table latch to permit the free rotation of the table and to engage the table clutch for effecting such rotation while the feed screw clutch is held in neutral.

Another feature of this invention resides in the provision of a cam member associated with the stop means on the table and adapted to engage a lever member associated with the trip mechanism which will simultaneously disengage the table clutch, move the table latch into a position in which it will engage a stop on the table, and reengage the screw clutch so that immediately upon the table being locked into position the screw becomes operative to initiate the downward movement of the spray gun relative to the next set of rotating drums.

It is a further object of this invention to embody in the trip mechanism, referred to above, a reciprocable shifter rod, the upper end of which is received in a socket provided with valves and conduits so as to form a compact automatic oil pump for spraying lubricant upon the screw and its associated mechanism during all periods at which the machine is operated.

Another important feature in the machine contemplated by this invention, is that the table and its associated parts are so constructed as to balance the momentum of the driving mechanism. In other words, the main driving gear which engages the driving shaft is always engaged. The table clutch merely locks the table to a ring gear associated with the main driving gear so that the momentum is either stored in the rotating table or in the drums (which, incidently, do not rotate during the movement of the table) and is consequently never lost or wasted.

It is a further object of this invention to produce a device of the class described which can be adjusted for operation on drums or objects of any desired width.

A still further object of the invention is to provide the machine with manually adjustable means for locking the screw clutch and the trip mechanism which actuates the table clutch in a neutral position.

The machine contemplated by this invention is entirely automatic in its operation, the only manual operations necessary being the replacement of the unsurfaced drums, which replacement can be effected simultaneously with the surfacing of another drum or set of drums.

The details in the construction of a preferred embodiment of my invention, together with other objects attending its production, will be best understood from the following description of the accompanying drawings which are chosen for illustrative purposes only, and in which—

Fig. 1 is a perspective view illustrating a preferred embodiment of my invention and showing the same equipped with brake drums and with two spray guns in operating position;

Fig. 2 is a fragmentary plan view partly broken away and showing the brake drums as having been removed;

Fig. 3 is a fragmentary sectional elevation which may be considered as having been taken in a plane represented by the line 3—3 in Fig. 2,

and is shown with the table member having been rotated through substantially 45° in order to bring a drum supporting portion thereof in the section plane;

Fig. 4 is an elevational view which may be considered as having been taken in the direction of the arrow 4 in Fig. 1 and which shows the rear face of the machine contemplated by this invention;

Fig. 5 is a sectional elevation taken in a plane 10 represented by the line 5—5 in Fig. 4 illustrating the construction of the feed screw and its associated parts;

Fig. 6 is a fragmentary plan section taken in a plane represented by the broken line 6—6 in Fig. 5;

Fig. 12 is a sectional view taken in a plane represented by the line 12—12 in Fig. 10;

Figs. 13 to 16 inclusive are diagrammatic views illustrating the various steps in the operation of the latch mechanism, the trip mechanism, the table clutch, and the screw clutch;

Fig. 17 is a sectional view of a brake drum illustrating the manner of applying the sprayed metal; and

Fig. 18 is a fragmentary section illustrating the character of the metal coating.

More particularly describing the invention as herein illustrated, reference letter A indicates a base plate or a base member which carries a table support generally indicated by reference letter B, which in turn rotatably supports a table indicated at C. The table C is adapted to be intermittently rotated through a clutch and gear mechanism, which will hereinafter be more fully described, from a main drive shaft D. While the table is held in a stationary position, by means of a latch mechanism, generally indicated at E, the main drive shaft D is effective to rotate a plurality of chucks F which carry spindles G upon which brake drums H are mounted.

The latch mechanism E is constructed and positioned so that it holds the table in a position where one or more of the drums H are held in alignment with the nozzle portions of metal spray guns I and I' which are mounted upon gun supporting brackets J and J'. The brackets J and J' are mounted on the end portions of an inverted T-head K which is in turn mounted for adjustment in a sleeve L formed on the end of a supporting arm M. The arm M has one end slidably mounted in a guide or way formed on the face of an upright housing O which contains means for imparting up and down movement to the arm M, such means being actuated by the main drive shaft D. The shaft D is driven through the medium of a chain drive or other suitable driving means P (see Fig. 4) from a motor Q.

The metal spray guns I and I' may be of any conventional type, suffice it to say at this time for the purpose of clearly describing the inven-

tion that each of these guns comprises a nozzle member 11 which is provided with a connection 12 for receiving a mixture of oxygen and acetylene delivered thereto through a suitable header indicated at 13 mounted on the housing 14 from hoses 15 and 15'. Another conduit 16 which is connected through a valve in the housing (not shown) to another hose 17 is provided for delivering compressed air to the nozzle.

Reference numeral 18 indicates a wire or rod which is fed into the nozzle 11 by a suitable feed and straightening mechanism contained within the housing 14, such wire or rod coming from a reel or other suitable source not shown. As the wire 18 is fed into the nozzle 11, it is melted by the oxyacetylene flame and is disseminated and deposited by the compressed air on the interior of the drum H which is being revolved through the drum revolving mechanism which will be described later.

The nozzle housing 14 is mounted upon a plate 19 which is adapted to be adjusted longitudinally of the nozzle supporting bracket J by means of a screw 20 and a hand wheel. When two guns are being used in the manner shown, it is preferable to adjust one gun for use on "rear" drums, and the other for "front" drums. Since the mountings for the front and rear drums are different, this permits the coating of a complete set of drums at one operation.

The machine is constructed and operated so that the table C is rotated into a position at which two of the drums H are positioned below the two nozzles where it is latched by the latch mechanism E. The latching of the table is automatically effective to initiate the downward movement of the supporting arm M. When the nozzles have reached a position at which they are spraying the lower edge of the wearing surface of the drums, the machine having been previously set for the proper drum width, the mechanism which operates the arm is automatically reversed without disturbing the table and the arm is raised to its upper position at which the latch is automatically released to permit the rotation of the table and means, to be described later, are brought into play for turning the table into the next position at which another set of drums is in alignment with the nozzles and the operation is repeated.

Referring now to the details in the construction of the table and its associated parts which are best illustrated in Figs. 2 and 3, reference numeral 23 indicates an upright spindle which is secured at its lower end in a collar 24 mounted in an opening 25 formed in the base member A and secured in such opening by means of screws 26. The spindle 23 has a shoulder 27 formed on an intermediate portion thereof, such shoulder supporting a combination thrust and radial bearing 28 which, in turn, supports a sleeve member 29. The sleeve member 29 is supported near its upper end by radial bearings 30 engaging the spindle 23 and above the bearing 30 the sleeve is formed with a hub portion 31 through which a threaded pin 32 extends. The outer surface of the hub portion 31 terminates at its lower end in a shoulder 33 which supports a downwardly extending hub collar 34 formed in the table. This hub collar is keyed to the hub portion 31 of the sleeve as indicated at 35 and is held in proper alignment therewith by means of a washer 36 which is engaged by a nut 37 mounted on the upper threaded end of the pin 32.

The table C is shown as comprising a plurality of radially extending wing members 38 which are either formed or mounted on the table hub section 34 and the entire unit is provided with a downwardly extending protecting flange 39.

The drum or work supporting chucks F, which have been referred to above, are formed at their upper ends with shoulders 40 which engage ball bearings 41 mounted in passages 42 formed in the ends of the wings 38. These passages 42, 10 in the form shown, comprise sleeves which are cast in the wing members and project downwardly relative to the upper faces of such members. The lower ends of the sleeves are provided with bearings indicated at 43. It will be 15 understood, of course, that the construction followed for each of the chucks is the same as that shown in Fig. 3 where the lower end of the chuck member F is shown as being of reduced diameter and is provided with a miter gear 44 keyed 20 thereto.

This miter gear 44 engages a pinion 45 which is mounted on the end of a chuck operating shaft 46 supported by bearings 47 which in turn are secured to the undersurface of the wing member 25 38. The inner end of the chuck operating shaft 46 is keyed to a pinion 48 which engages a miter gear 49 mounted, through the medium of bolts 50, upon a chuck driving sleeve 51. The upper end of the chuck driving sleeve 51 engages a collar 52 30 which forms a top bearing against the table rotating sleeve 29. The lower end of the chuck operating sleeve is mounted upon another bearing collar 53, the inner surface of which engages the table operating sleeve 29 and the lower edge of 35 which rests upon a flange 54 formed on the lower edge of the table operating sleeve.

Reference numeral 56 indicates a main drive gear, and reference numeral 57 indicates a driving clutch member, both of which are rigidly secured through the medium of pins or bolts 58 to a flange 59 formed on the chuck operating sleeve 51. This main drive gear 56 is engaged by a pinion 60 keyed to the inner end of the main drive shaft D which is shown as being supported at its 45 inner end by a bearing standard 61 mounted on the base member A.

Reference numeral 62 indicates a clutch plate having a clutch face 63 adapted to engage a corresponding face 64 formed on the lower end of the 50 driving clutch member 57. This clutch plate 62, which is provided with rigid pins 65 extending upwardly into pin recesses 66 formed in the bottom of the table operating sleeve 29, rests upon a bearing 68 mounted in a clutch engaging collar 69 which is adjustably mounted on a nut 69' in threaded engagement with threads 70 formed on the main spindle 23. This collar 69 is adapted to be rotated through the action of the nut 69' on the threads 70 for moving the clutch plate 62 60 into engagement with the driving clutch member 57 by means of a clutch actuated rod 71 which has a stirrup 72 mounted on its end, which in turn has a pin connection to a lever arm 73 formed on the collar 69.

From the construction described so far, it will be observed that when the clutch is disengaged, in other words, when the collar 69 has been rotated downwardly in its threads to permit a clearance between the clutch plate and the clutch driving member, the table in the meantime having been locked against rotation, the rotation of the main drive shaft D and the consequent rotation of the gear 49 imparts rotation to the chuck driving shafts 46 and their associated parts, in- 75

cluding the chucks F, the spindles G and the brake drums H supported by the chucks.

When the table is released and the clutch actuating rod 71 is pulled to the right to rotate the clutch collar 69 in its threads and move the clutch plate 62 into engagement with the driving clutch element 57, the shaft D continuing to rotate drives the clutch plate 62 and consequently through the pins 65 rotates the sleeve 29 to which the table is keyed. At the same time the chuck operating shafts cease to rotate and the table is moved to its next position at which, as pointed out hereinabove, it engages a latch to lock it against further rotation and automatically disengage the clutch which permits the rotation of the shaft D to again be imparted to the chuck operating shafts 36.

In this form of my invention the clutch actuating rod 71 is pivotally connected, as indicated at 75, to a clutch actuating lever 76 which is rigidly mounted upon a clutch actuating shaft 77, the shaft 77 being supported in bearings 78 and 78' mounted on the base member A. The lever 76 is continually biased toward a clutch engaging position by means of a tension spring 79 which, as shown in Fig. 5, is secured to a rigid support 80 on the base member.

The latch mechanism E includes, what I may term, a latch member or a lever member 81 (see Figs. 10 and 12) the upper end portion of which engages a stop 82 mounted on the underside of a table wing. More specifically, the latch member or the lever member 81 comprises a supporting bracket 83 which is mounted on the shaft 77, such bracket having projecting ears 84 forming a recess in its upper end which receives the latch member 81 held therein by means of a pin 86. A second pair of projecting ears 87 form another recess on the bracket member through which the latch member 81 extends and in which such member is held by means of a bar or finger 88. The lower end of the latch member 81 is provided with a downwardly extending pin 89 which projects through a notch 90 formed in the lower end of the bracket member and a compression spring 91 encircles the pin 89 and is interposed between a shoulder 92 on the latch member and the foot portion 93 which contains the notch in the bracket. A tension spring 94 is interposed between the lower end of the pin 89 and a projection 95 formed on the lower end of the bracket.

When the latch mechanism is in the position shown in full lines in Fig. 12, the clutch actuating shaft 77 has been rotated to a position at which the clutch is disengaged and the table is held against further rotation by virtue of the engagement of the stop member 82 with the notch 85 in the latch member 81. It will be seen, therefore, that it is necessary to provide some means for moving the latch member 81 downwardly against the action of the compression spring 91 in order to permit the tension spring 79 acting upon the lever 76 to rotate the clutch engaging collar for reengaging the table clutch to rotate the table.

For the purpose of effecting this last mentioned operation, I mount upon the shaft 77 in rotatable relation thereto, a sleeve 100 which has one end in bearing engagement with the bracket member 83 and has mounted upon that end portion thereof a pawl or cam member 101. This cam member is arranged so as to engage a pin 102 which is mounted on the inside face of the latch member 81. When the table has just been stopped from rotation and the clutch disengaged,

the cam is situated with respect to the pin as shown in full lines in Figs. 10, 11, and 12.

In the operation of a trip mechanism of which the cam and sleeve are a part and which will be more completely described with relation to the mechanism for operating the traveling arm M, the sleeve and the cam are rotated upwardly to the broken line position shown in Fig. 12 where the flat portion of the cam nose rests upon or is situated above the pin 102. From the broken line position it will be seen that the next counter clockwise rotation of the cam and sleeve will be effective to press the latch member 81 downwardly against the action of the compression spring 91 so that its upper end clears the lower surface of the notch 82 in the stop 82, thereby permitting the clutch actuating shaft 77 to be rotated in the counterclockwise direction by the action of the tension spring 79 which will, through the action of the clutch actuating rod 71, engage the table clutch.

The rotation of the clutch actuating shaft 77 swings the latch member 81 into the dotted line position shown in Fig. 12 at which position the latch member 81 of itself will not effectively engage the stop member. It is, therefore, necessary to provide some means for rotating the latch mechanism and the clutch actuating shaft back to the full line position shown where the latch member 81 will engage the next stop on the table.

For the purpose of effecting this operation, I provide an elongated finger cam 103 on the undersurface of the table which is situated so as to engage a ball 104 mounted on the upper end portion of a crank or lever member 105 which, in view of the fact that it is a part of the trip mechanism referred to above, will hereinafter be referred to as a trip lever. This lever 105 is secured to the sleeve 100 through the medium of a screw or bolt 106 extending through a collar 107 which is locked to the sleeve by means of the set screw 108.

When the cam 103, by virtue of the rotation of the table, engages the ball 104 it swings the lever 105 together with the sleeve in a counterclockwise direction so that a forward face 105' on the lever or crank 105 engages the end of a screw 110 which is adjustably mounted in an extension of the bar 88. This movement is indicated in broken lines shown in Fig. 11. The continued movement of the finger cam 103, by virtue of the engagement between the trip lever 105 and the screw 110, swings the bracket and its associated latch member 81 into the full line position shown in Fig. 12 thereby disengaging the clutch and positioning the latch member 81 for engagement with the stop 82 on the table. In this connection it will be seen that the disengagement of the table clutch can be regulated by adjusting the screw 110.

Referring now to Figs. 5 to 9 inclusive for a more complete description of the upright housing O, the means for actuating the traveling arm, and the remainder of the trip mechanism, it will be observed that the housing O is provided with a base flange 120 whereby it is secured to the base member A through the medium of screws 121. The bottom of the housing and the flange connection are formed so as to provide an oil reservoir 122 in the bottom of the upright housing, the purpose of which will be more fully described later in the specification.

It will be observed from Fig. 5 that the main drive shaft D which has a bearing 61' on the base member adjacent the upright housing, extends

through bearings 124 and 124' provided in the bottom portion of the upright housing. The outwardly extending end of the main drive shaft is provided with a sprocket 125 which forms a part 5 of the driving means indicated at P, such sprocket and driving means being encased in a protecting housing 126.

Within the housing O, the shaft D is provided with a pair of spaced miter pinions 128 and 129 10 rotatably mounted on the shaft. The opposite inner faces 128' and 129' of the pinions are formed with clutch jaws adapted to be engaged by similar clutch jaws 130 and 131 formed on the ends of a clutch collar 132 which is splined 15 to that portion of the shaft D which lies between the two pinions 128 and 129.

The clutch collar 132 is provided with an annular groove 134 which receives a block 134' slidably mounted between compression springs 20 135 and upon a curved guide bar 135' which in turn is mounted in a fork 136 formed on the upper end of a lever member 136' which is keyed to a shaft 142. The block 134' and its associated mechanism is effective, through opposite rotations of the shaft 142, to move the clutch collar into engagement with the opposite clutch faces on the gears 128 and 129 and also, under certain operations of the trip mechanism to throw the clutch collar into a neutral position.

30 The pinions 128 and 129 are in engagement with a gear 137 which is keyed to the lower end portion of a feed screw 138. The feed screw 138 has its upper end portion rotatably mounted in a bearing 138 which is formed in a bearing bushing 138a mounted in the top of the housing, and the upwardly extending end of the feed screw is provided with a hand wheel 139 for manually operating the same. The lower end portion of the feed screw is supported in a combination 40 radial and thrust bearing 141 which is contained within a bearing housing 141'. The bearing housing 141' is secured to a bracket member 143 which projects through an opening 144 formed in the housing and which is secured, through 45 medium of screws 145, to a bearing supporting plate 146. This last mentioned plate is mounted upon the face of the housing through the medium of screws 147 (see Figs. 1 and 7).

For the purpose of properly aligning the lower bearing I provide shims 149 which are interposed 50 between the plate 146 and the engaged surface of the housing.

The front face of the housing O is provided with an elongated opening or way 151 wherein 55 a feed nut yoke member 152, mounted on the back of the arm M as indicated at 153, is adapted to move. The feed nut yoke member 152 extends partially around a feed nut or traveling member 153' which is in threaded engagement with the 60 feed screw, and is provided with blocks 154 pivotally mounted thereon, such blocks being received in notches 155 formed in the feed nut yoke 152.

On opposite sides of the opening 151 in the 65 housing O, I provide a pair of undercut plates 157 which are secured thereto by means of screws 158. The undercut portions of these plates 157 receive inwardly extending projections 159 on gib plates 160, such gib plates being 70 mounted by means of bolts 161 upon the edges of a supporting plate 162 which, in this form of my invention, is cast to the rear end portion of the arm M.

The top of the plate section 162 is shown as 75 being provided with a shield plate 164 which is

formed so that it extends at all times over the opening 151 to prevent lubricant being sprayed through the opening onto the machine.

From the construction so far described, it will be seen that as the clutch collar is moved from a neutral position into engagement with the clutch faces on either of the pinions 128 or 129 the feed screw will, through the action of the gear 135, be rotated in opposite directions to move the traveling member 153 and its associated 10 parts including the arm M up or down as the case may be. In this connection it is again pointed out that the main shaft D continues to rotate in the same direction, the operation of the feed screw being controlled solely by the action of the 15 feed screw clutch.

Since the intermittent rotation of the table in the manner described above, and the automatic reversal of the movement of the arm is dependent upon the extent of movement in the arm or the 20 position of the nozzles with respect to the drums, it is important that the trip mechanism, which has been partially described hereinabove, include as an element, means which are actuated by the traveling member or some of its associated parts. 25 In this form of my invention, I provide the traveling member or feed nut 153 with an arm or extension 170, the end of which is provided with a collar 171 slidably engaging a bar or rod 172 which I will hereinafter refer to as a trip bar. 30 This trip bar has its upper end slidably fitted into a cylinder 173 of a socket member 174 which is secured in an opening in the top of the housing O by means of a flange connection 175. The bottom of the trip bar 172 is secured, through 35 the medium of a stirrup and pin connection 176, to a lever member 177 which is rigidly secured to the shaft 142 (see Fig. 9).

Mounted on the trip bar 172 at the bottom of the travel of the feed nut 153, is a stop member 180 which supports a compression spring 181. The compression spring 181 is adapted to be engaged by the collar 171 and through such engagement it is compressed against the stop 180 to a point at which the lever 177 is moved downwardly rotating the shaft 142 in a clockwise direction, and since, under these circumstances the feed nut is moving downwardly, the clutch jaw 130 on the clutch collar 132 is engaged with the corresponding clutch jaw 128' on the gear 128 which rotates the shaft for downward movement of the feed nut, therefore, the clockwise rotation of the shaft 142, through the action of the fork lever 136, disengages the clutch, and the expansion of the compression spring 181 throws the 55 clutch collar the full width of the gap into engagement with the pinion 129 which reverses the rotation of the feed screw.

For the purpose of limiting the upward movement of the feed nut, I provide the trip bar 172 with another stop member 185, such stop having a projecting handle 186 which extends through a slot 187 formed in a cover plate 188 on the back of the housing O. This handle member is provided with a latch mechanism generally indicated at 189, the keeper of which is adapted to be received in notches 190 formed on the trip bar. It is to be understood that this stop member may be adjusted to control the upward limit of travel of the arm M and its associated parts. 70

Reference numeral 192 indicates a compression spring which is situated on top of the collar member 171 and which is adapted to be compressed between the stop 185 and the collar 171 when the collar reaches its upper limit of travel. 75

As this spring is compressed, the trip bar 172 is gradually moved upward to move the clutch collar 132 into its neutral position. It will be observed that the spring 192 is lighter or shorter than the spring 181 so that the action of this 5 spring is merely sufficient to disengage the clutch collar but will not throw it across the gap and into engagement with the other gear.

As was pointed out hereinabove, the trip bar has, in addition to the functions just named, 10 the function of releasing the table latch so as to permit the engagement of the table clutch when the arm M reaches its uppermost position. This function is accomplished through the medium of a latch actuating bar 200 which is slidably mounted in bearings 201 and 202 formed in opposite sides of the housing O.

The bar 200 is provided with a pin 203 which extends into the fork 204 in the upper end of a lever 205 rigidly mounted upon the shaft 142. 20 Various rotative movements of the shaft 142 are, therefore, effective to reciprocate the bar 200, and for the purpose of stopping and releasably holding the bar in the three alternative positions which correspond to the up, neutral, and down 25 positions of the clutch collar 132, I provide the bar with three notches indicated generally by reference numeral 207 which are adapted to selectively receive a spring pressed ball 208 mounted in the bearing member 201. The bar 200 is connected, through a yieldable spring connection 209, with a rod 210 which in turn is secured at its end and through a yoke 211 to a crank 213 rigidly mounted upon the sleeve 100 (see Fig. 3).

In addition to forming a part of the trip mechanism, the trip bar 172 comprises part of a novel pump whereby lubricant is continuously supplied to the feed screw and its associated parts during the operation of the machine. As was pointed out above, the upper end of the trip bar 172 is 40 fitted in sliding engagement into the cylinder 173 formed in the socket member. This cylinder is provided at its upper end with a fluid inlet connection 215 and a fluid outlet connection 216, the inlet connection 215 being connected through 45 a check valve 217 with an inlet conduit 218 which opens at its lower end into the oil reservoir 122.

The fluid outlet connection 216 is connected through a check valve 220 with an outlet conduit 221 which opens into a space provided in the top 50 feed screw bearing 138. As the trip rod 172 is moved downwardly through the action of the collar 171 on the stop 180, oil is drawn into the cylinder 173 through the check valve 217 from the oil reservoir. When the collar member 171 55 reaches the upper limit of the stroke and engages the stop member 185, moving the trip rod 172 upwardly, the oil thus received is forced out through the check valve 220 and onto the feed screw 136, across which it is returned to the oil 60 reservoir.

For the purpose of protecting the bottom bearing 141 against grit or cuttings which may be carried by the oil, I provide a felt ring 225, or a 65 plurality of such rings, in the bearing housing 141.

As was pointed out above, the upward movement of the traveling member or feed nut, gradually moves the trip rod 172 upwardly until the clutch is disengaged. This movement is also effective to release the table and engage the table 70 clutch. As the table rotates around into its next position, the finger cam 103, through its engagement with the knob 104, rotates the sleeve and through the action of the crank 213 and the rod

210 quickly pulls the rod 200 forward thereby giving a final upward thrust to the trip bar 172. During this final thrust the trip bar moves much more rapidly than it does during the first part of its motion when the clutch is disengaged and the 5 outlet valve 220 was not large enough to take care of this rapid upward movement.

For the purpose of quickly releasing the remainder of the oil contained in the cylinder 173, I provide an auxiliary outlet 221 in the top of the 10 socket member 174. This auxiliary outlet is normally closed by a spring pressed check valve 228 which may be adjusted to give the desired hydraulic cushioning effect to the trip rod 172 by means of an adjusting screw 229. Since the 15 movement is imparted to the trip rod directly from the table, it will be seen that this structure provides a hydraulic cushion for the table stop and latch mechanism.

For the purpose of optionally locking the clutch 20 132 in neutral at the end of the downward movement of the feed nut, I provide the trip bar 172 with a neutral locking handle 230 which projects through an opening 231 in a bottom cover plate 232 on the back of the housing O. Below the 25 extending portion of this lever, I provide a cam plate 233 which is pivotally attached to the cover plate as indicated at 234, such cam plate being provided with a handle 235. When the cam plate 233 is swung into the full line position 30 shown in Fig. 4, it will be engaged by the handle member 230 and will thereby hold the trip bar 172 against further downward movement beyond the position at which the feed screw clutch 35 132 is in neutral.

Referring to Figs. 13 to 16 inclusive, the operation of the trip mechanism, the feed screw clutch, the table latch, and the table clutch is as follows: Referring to Fig. 13 the table member with the finger cam 103 has just been rotated to 40 a position at which the finger cam has passed the ball 104, the table having been brought into a position at which the stop 82 is engaged with the latch 85, the table clutch 62 having been disengaged and the feed screw clutch 132 having 45 been thrown into engagement with the "down" gear 128, thus initiating the rotation of the feed screw in a direction which imparts downward movement to the feed nut 153. It will be observed that in this position the curved nose of 50 the cam 101 rests beneath the pin 102.

As the feed nut 153 travels downwardly, it is brought into engagement with the stop 180 as shown in broken lines in Fig. 13, compressing the spring 181, thus gradually releasing the clutch 55 collar from the gear 128 against the action of the spring pressed ball 208 in the last notch with which it is in engagement. When the clutch is released in this manner the latch compression spring 181 is effective to throw the clutch collar 60 clear through the neutral position and into engagement with the "up" gear 129 to the position as shown in Fig. 14.

The movement of the sectional bar 200-210 which accompanies the shift just described, rotates the sleeve 100 so that the nose of the cam 101 passes the pin 102 and assumes a position at which the flat portion of the cam is situated above or rests upon the pin 102. The feed nut 153 is now moving in an upward direction as indicated in Fig. 14. When the nut reaches its upper limit of travel, as indicated at Fig. 15, the top spring 192 is compressed against the stop 185, the continued upward movement of the feed nut being effective to move the upright 70 75

shifter rod 172 upwardly, gradually withdrawing the clutch collar 132 from its engagement with the "up" gear 129 until it occupies a neutral position where the ball 208 is engaged in the 5 central notch 207. This movement of the sectional rod 200-210 rotates the flat face of the cam 100 downwardly against the pin 102 thus moving the latch 85 into a position at which it clears the notch in the stop 82. This permits the 10 table clutch actuating shaft 71 to be rotated by the action of the tension spring 79 in a clutch engaging direction which engages the table clutch, thereby initiating the rotation of the table.

Fig. 15 shows the clutch as having been engaged and illustrates the next cam and stop on the table as being in a position just prior to the engagement of the cam 103 with the ball 194 on the sleeve supported lever 105. The continued movement of the table rotates the lever 20 rearwardly into the position shown in Fig. 16 at which the latch member 85 is swung up into a position at which it will be engaged by the stop member 82. This movement also disengages the clutch and swings the segmental bar 200-210 25 forwardly into the position in Fig. 13; also engaging the feed screw clutch with the "down" gear 128 and giving a final upward thrust to the trip bar 172.

Fig. 17 illustrates more clearly the manner in 30 which the metal is sprayed onto the interior of the brake drum. As was pointed out above, the T-head K is adjusted so that the spray will just strike the rim of the drum, and the downward movement imparted to the nozzles from the feed 35 screw is so related to the rotation of the drum that the nozzles are moved, say, one-third the width of the area covered by the spray for each rotation of the drum. This results in an overlapping series of layers which forms the mat of 40 hard metal on the inner surface of the drum, such layers being indicated at L1, L2, and L3 in Fig. 18. As the nozzles traverse their upward course, another series of layers are laid on the wearing surface so that the surface (in the event 45 the relative movement between the nozzle and the drum is as pointed out above) will be made up of six thicknesses of metal. It will be understood of course that each drum may be given as many applications as desired to obtain the required thickness, but the operation of the machine is such that the deposited metal is permitted to set after each depositing operation, but not to harden to an extent preventing secure bonding together of the successive spray-deposited layers.

It will be seen from the foregoing description that when the table has stopped in a position for spraying one set of drums, the other set of drums is free to be removed and replaced with an 55 untreated or unlined set. The operation of the machine is entirely automatic and the only manual operations are those just mentioned in connection with the drums.

It is again emphasized that the method and 60 apparatus contemplated by this invention is not confined to use in repairing worn or scored drums, but that it may be used in placing upon a new drum, a wearing surface having greater hardness and durability and a higher coefficient of friction than can be obtained in an original forging or 65 casting.

It is to be understood that, while I have herein described and illustrated one preferred form of my invention, the invention is not limited to the 70 precise construction described herein, but in-

cludes within its scope whatever changes fairly come within the spirit of the appended claims.

I claim as my invention:

1. A machine for applying a metal coating to 5 brake drums and the like embodying: a table; means for rotatably supporting said table; means on said table for supporting a plurality of drums; means including a main gear for rotating said drum supporting means, said main gear being coaxial with the table support; a metal spray 10 gun; means for supporting said spray gun above said table; means for effecting relative up and down movement between a drum engaged by said drum supporting means and said spray gun; latch means for normally holding said table in a fixed 15 position relative to said spray gun; means including a clutch, which is coaxial with the table support and is adapted to be driven by said main gear, for rotating said table; and automatic means for releasing said table and engaging said 20 table rotating clutch when a predetermined position of said spray gun relative to said drum has been reached.

2. A machine for applying a metal coating to 25 brake drums and the like embodying: a table; means for rotatably supporting said table; means on said table for supporting a plurality of drums; means, including a main gear coaxial with said table support, for rotating said drum supporting means; a metal spray gun; means for supporting 30 said spray gun above said table; means for effecting relative up and down movement between a drum engaged by said drum supporting means and said spray gun; latch means for normally holding said table in a fixed position relative to 35 said spray gun; means including a clutch, which is coaxial with the table supporting means and is adapted to be driven by said main gear, for rotating said table; automatic means for releasing said table and engaging said table rotating clutch 40 when a predetermined position of said spray gun relative to said drum has been reached; and means on said table for engaging said latch to lock said table against further rotation when it has been rotated to a predetermined position 45 relative to said spray gun.

3. A machine for applying a metal coating to 50 brake drums and the like embodying: a table; means for rotatably supporting said table; means on said table for supporting a plurality of drums; means including a main gear for rotating said drum supporting means; a metal spray gun; means for supporting 55 said spray gun above said table; means for effecting relative up and down movement between a drum engaged by said drum supporting means and said spray gun; latch means for normally holding said table in a fixed position relative to said spray gun; means including a clutch element formed integrally with said main gear for rotating said table; automatic 60 means for releasing said table and engaging said table rotating clutch when a predetermined position of said spray gun relative to said drum has been reached; and means operable by said automatic means for disengaging said means 65 which effect the up and down movement between said spray gun and said drum.

4. A machine for applying a metal coating to 70 brake drums and the like embodying: a table; means for rotatably supporting said table; means on said table for supporting a plurality of drums; means including a main gear for rotating said drum supporting means; a metal spray gun; means for supporting 75 said spray gun above said table; means for effecting relative up and down

movement between a drum engaged by said drum supporting means and said spray gun; latch means for normally holding said table in a fixed position relative to said spray gun; means including a clutch element formed integrally with said main gear for rotating said table; automatic means for releasing said table latch and engaging said table rotating clutch when a predetermined position of said spray gun relative to 10 said drum has been reached; means operable by said automatic means for disengaging said means which effect the up and down movement between said spray gun and said drum, means on said table for engaging said latch to lock said table 15 against further rotation when it has been rotated to a predetermined position relative to said spray gun; and means operable by said latch for re-engaging the means which effect said up and down movement between the spray gun and the 20 drum.

5. A machine for applying a metal coating to brake drums and the like embodying: a table; means for rotatably supporting said table; means including a main gear and a clutch for rotating 25 said table, said main gear and clutch being co-axial with respect to the table-supporting means; means for supporting a plurality of drums on said table; means actuated by said main gear when said table is stationary for rotating said drums; 30 a metal spray gun; means for supporting said spray gun above said table; means for moving said spray gun support downwardly toward said table; and automatic means operable when said spray gun support has reached a predetermined 35 downward position to reverse the direction of movement of said spray gun support.

6. A machine for applying a metal coating to brake drums and the like embodying: a table; means for rotatably supporting said table; means 40 including a main gear and a clutch for rotating said table, said main gear and clutch being co-axial with respect to the table-supporting means; means for supporting a plurality of drums on said table; means actuated by said main gear 45 when said table is stationary for rotating said drums; a metal spray gun; means for supporting said spray gun above said table; latch means for locking said table with one of said drums in a predetermined position relative to said spray 50 gun; means for moving said spray gun support downwardly toward said table; automatic means operable when said spray gun support has reached a predetermined position to reverse the direction of said spray gun support moving 55 means; and automatic means operable when said spray gun support has reached a predetermined upward position to disengage said spray gun support moving means.

7. A machine for applying a metal coating to 60 brake drums and the like embodying: a table; means for rotatably supporting said table; means including a main gear and a clutch for rotating said table, said main gear and clutch being co-axial with respect to the table-supporting 65 means; means for supporting a plurality of drums on said table; means actuated by said main gear when said clutch is disengaged for rotating said drums; a metal spray gun; means for supporting said spray gun above said table; latch means for locking said table with one of said 70 drums in a predetermined position relative to said spray gun; means for moving said spray gun support downwardly toward said table; automatic means operable when said spray gun support has reached a predetermined position to reverse the 75

direction of said spray gun support moving means; automatic means operable when said spray gun support has reached a predetermined upward position to disengage said spray gun support moving means; and means operable by 5 said last mentioned automatic means for releasing said table holding latch and engaging said table rotating clutch.

8. A machine for applying a metal coating to brake drums and the like embodying: a table; 10 means for rotatably supporting said table; means including a main gear and a clutch for rotating said table, said main gear and clutch being co-axial with respect to the table-supporting means; means for supporting a plurality of drums on 15 said table; means engaging said main gear for rotating said drums when said clutch is disengaged; a metal spray gun; means for supporting said spray gun above said table; latch means for locking said table with one of said drums in a 20 predetermined position relative to said spray gun; means for moving said spray gun support downwardly toward said table; automatic means operable when said spray gun support has reached a predetermined position to reverse the direction of 25 said spray gun support moving means; automatic means operable when said spray gun support has reached a predetermined upward position to disengage said spray gun support moving means; means operable by said last mentioned automatic means for releasing said table holding latch and engaging said table rotating clutch; and stop means on said table for engaging said latch to hold said table against further rotation when it reaches a predetermined 30 position relative to said spray gun.

9. A machine for applying a metal coating to brake drums and the like embodying: a table; means for rotatably supporting said table; means including a main gear and a clutch for rotating 40 said table, said main gear and clutch being co-axial with respect to the table-supporting means; means for supporting a plurality of drums on said table; means engaging said main gear for rotating said drum; a metal spray gun; means 45 for supporting said spray gun above said table; latch means for locking said table with one of said drums in a predetermined position relative to said spray gun; means for moving said spray gun support downwardly toward said table; automatic means operable when said spray gun support has reached a predetermined position to reverse the direction of said spray gun support moving means; and automatic means operable when said spray gun support has reached a 50 predetermined upward position to disengage said spray gun support moving means; means operable by said last mentioned automatic means for releasing said table holding latch and engaging said table rotating clutch; stop clutch on 60 said table for engaging said latch to hold said table against further rotation when it reaches a predetermined position relative to said spray gun; and means operable by said latch when engaged by said stop means for disengaging said table rotating means and reengaging said downwardly operating spray gun support moving means.

10. A machine for applying a metal coating to 70 brake drums and the like embodying: a table; means for rotatably supporting said table; means including a main gear and a clutch for rotating said table, said main gear and clutch being co-axial with respect to the table-supporting means; means for supporting a plurality of drums on 75

5 said table; means engaging said main gear for rotating said drums; a metal spray gun; adjustable means for supporting said spray gun above said table; means for moving said spray gun support downwardly toward said table; and automatic means operable when said spray gun support has reached a predetermined downward position to reverse the direction of movement of said spray gun support.

10 11. A machine for applying a metal coating to brake drums and the like embodying: a table; means for rotatably supporting said table; means including a main gear and a clutch for rotating said table; means for supporting a plurality of drums on said table; means engaging said main gear for rotating said drums when said clutch is disengaged; a metal spray gun; adjustable means for supporting said spray gun above said table; latch means for locking said table with one of 15 said drums in a predetermined position relative to said spray gun; means for moving said spray gun support downwardly toward said table; automatic means operable when said spray gun support has reached a predetermined position to 20 reverse the direction of said spray gun support moving means; and automatic means including an adjustable stop operable when said spray gun support has reached a predetermined upward position to disengage said spray gun support moving means.

12. A machine for applying a metal coating to 25 brake drums and the like embodying: a table; means for rotatably supporting said table; means for rotatably supporting a plurality of brake drums on said table; a main drive shaft; means including a main gear, coaxial with the table-supporting means, for rotating said drum supports from said main drive shaft; means including a table clutch associated with said gear for 30 rotating said table from said main drive shaft, said table clutch being coaxial with the table-supporting means; an upright housing arranged in offset relation with the axis of said table; guide means on said housings; a spray gun supporting arm 35 slidably mounted on said guide means; a spray gun mounted on said arm above said table; means including an upright feed screw in said housing for moving said arm; and means including a clutch on said main drive shaft for 40 rotating said feed screw in opposite directions.

13. A machine for applying a metal coating to 45 brake drums and the like embodying: a base member; a table; means on said base member for rotatably supporting said table; means for rotatably supporting a plurality of brake drums on said table; a main drive shaft; means including a main gear coaxial with said table-supporting means for rotating said drum supports from said main drive shaft; means including a table clutch 50 coaxial with said table-supporting means for rotating said table from said main drive shaft; an upright housing mounted on said base member in offset relation with said table; guide means on said housing; a spray gun supporting arm slidably mounted on said guide means; a metal spray gun mounted on said arm above said table; an upright feed screw in said housing; means including a clutch member on said main drive shaft for driving said feed screw in opposite directions; means including a travelling member on said feed screw for imparting up and down movement to said arm; and means engageable by said travelling member to throw said feed screw clutch and reverse the rotation of said 55 feed screw.

14. A machine for applying a metal coating to 60 brake drums and the like embodying: a base member; a table; means on said base member for rotatably supporting said table; means for rotatably supporting a plurality of brake drums on said table; a main drive shaft; means including a main gear coaxial with said table-supporting means for rotating said table from said main drive shaft; an upright housing mounted on said base member in offset relation with said table; guide means on said housing; a spray gun supporting arm slidably mounted on said guide means; a metal spray gun mounted on said arm above said table; an upright feed screw in said housing; means including a clutch member on said main drive shaft for driving said feed screw in opposite directions; means including a traveling member on said feed screw for imparting up and down movement to said arm; an upright shifter rod reciprocably mounted in said housing; stops on said shifter rod adapted to be engaged by said traveling member; and means at the lower end of said shifter rod for throwing said feed screw clutch.

15. A machine for spraying brake drums and the like embodying: a table; means for rotatably supporting said table; means for rotatably supporting a plurality of brake drums on said table; a main drive shaft; means for rotating said drum supports from said main drive shaft; means including a table clutch for rotating said table from said main drive shaft; an upright housing; guide means on said housing; a spray gun supporting arm slidably mounted on said guide means; a spray gun mounted on said arm above said table; an upright feed screw in said housing; means including a clutch member on said main drive shaft for driving said feed screw in opposite directions; means including a traveling member on said feed screw for imparting up and down movement to said arm; a socket in the top of said housing; an upright shifter rod 45 having its upper end portion reciprocably mounted in said socket; an inlet port and an outlet port in the top of said socket; valves in said ports; a conduit leading from said inlet port to an oil reservoir in the bottom of said housing; a discharge conduit in said outlet port having an outlet adjacent said feed screw; stops on said shifter rod adapted to be engaged by said traveling member for reciprocating said rod; and means at the lower end of said rod for throwing said feed 50 screw clutch.

16. A machine for applying a metal coating to 55 brake drums and the like embodying: a base member; a table; means on said base member for rotatably supporting said table; means for rotatably supporting a plurality of brake drums on said table; a main drive shaft; means including a main gear coaxial with the table-supporting means for rotating said drum supports from said main drive shaft; means including a table clutch 60 coaxial with the table-supporting means for rotating said table from said main drive shaft; an upright housing mounted on said base member in offset relation with said table; guide means on said housing; a spray gun supporting arm slidably mounted on said guide means; a metal spray gun mounted on said arm above said table; a feed screw bearing in the top of said housing; a feed screw having its upper end mounted in said bearing; a bottom feed screw bearing adjustably 65

mounted in the bottom of said housing; a traveling member on said feed screw for moving said arm in said guide; and means including a clutch member on said main drive shaft for rotating said feed screw in opposite directions.

17. A machine for applying a metal coating to brake drums and the like embodying a base member; a table; means on said base member for rotatably supporting said table; means for rotatably supporting a plurality of brake drums on said table; a main drive shaft; means including a main gear coaxial with the table supporting means for rotating said drum supports from said main drive shaft; means including a table clutch coaxial with the table-supporting means for rotating said table from said main drive shaft; an upright housing mounted on said base member in offset relation with said table; guide means on said housing; a spray gun supporting arm slidably mounted on said guide means; a metal spray gun mounted on said arm above said table; means including an upright feed screw in said housing for moving said arm; means including a clutch on said main drive shaft for rotating said feed screw in opposite directions; and adjustable means for locking said clutch in a neutral position.

18. In a device of the class described: a table; means for supporting work on said table; means for rotatably supporting said table; means including a clutch and a main gear, both coaxial with said table-supporting means for rotating said table; a main drive shaft for driving said main gear and, table clutch; a table clutch operating shaft; means on said table clutch operating shaft for actuating said table clutch; yieldable means for moving said table clutch actuating means to engage said table clutch; a latch member on said clutch operating shaft; a stop on said table adapted to engage said latch and hold said table clutch in disengagement against the action of said yieldable means; and means for releasing said latch means from said stop to permit the engagement of said clutch by said yieldable means.

19. In a device of the class described: a rotatable work-supporting table; a support for said table; means including a main gear and a clutch both coaxial with the table support for rotating said table; a horizontal main drive shaft for driving said table clutch; bearing means supporting said main drive shaft; an upright guide member adjacent said table in offset relation therewith; a traveling arm having a portion thereof engaged in said guide member and an extending portion projecting above said table; an upright feed screw mounted adjacent said guide member; bearing means supporting said feed screw; a traveling member on said feed screw; means engaged by said traveling member for moving said arm; means including a reversing clutch on said main drive shaft for rotating said feed screw in opposite directions; and trip means adapted to be engaged by said traveling member for throwing said feed screw clutch.

20. In a device of the class described: a rotatable work supporting table; a support for said table, means including a main gear and a clutch both coaxial with the table-supporting means for rotating said table; a main drive shaft for driving said table clutch; bearing means supporting said main drive shaft; an upright guide member adjacent said table in offset relation therewith; a traveling arm having a portion thereof engaged in said guide member and an extending portion

projecting above said table; an upright feed screw mounted adjacent said guide member; bearing means supporting said feed screw; a traveling member on said feed screw; means engaged by said traveling member for moving said arm; means including a reversing clutch on said main drive shaft for rotating said feed screw in opposite directions; means including a yieldable member for engaging said table clutch; latch means actuated by said table for holding said table clutch in disengagement against the action of said yieldable means; trip means adapted to be engaged by said traveling member for releasing said latch to permit the rotation of said table and the engagement of said clutch; and means operable by said latch means for disengaging said feed screw clutch.

21. In a device of the class described: a rotatable work supporting table; a support for said table, means including a main gear and a clutch both coaxial with the table-supporting means for rotating said table; a main drive shaft for driving said table clutch; bearing means supporting said main drive shaft; an upright guide member adjacent said table in offset relation therewith; a traveling arm having a portion thereof engaged in said guide member and an extending portion projecting above said table; an upright feed screw mounted adjacent said guide member; bearing means supporting said feed screw; a traveling member on said feed screw; means engaged by said traveling member for moving said arm; means including a reversing clutch on said main drive shaft for rotating said feed screw in opposite directions; means including a yieldable member for engaging said table clutch; latch means actuated by said table for holding said table clutch in disengagement against the action of said yieldable means; trip means adapted to be engaged by said traveling member for releasing said latch to permit the rotation of said table and the engagement of said clutch; means operable by said latch means for disengaging said feed screw clutch; and means including a cam member on said table and a lever member in said trip mechanism engageable therewith after a predetermined rotation of said table for disengaging said table clutch and reengaging said feed screw clutch.

22. In a device of the class described: a rotatable work supporting table; a support for said table, means including a main gear and a clutch both coaxial with the table-supporting means for rotating said table; a main drive shaft for driving said table clutch; bearing means supporting said main drive shaft; an upright guide member adjacent said table in offset relation therewith; a traveling arm having a portion thereof engaged in said guide member and an extending portion projecting above said table; an upright feed screw mounted adjacent said guide member; bearing means supporting said feed screw; a traveling member on said feed screw; means engaged by said traveling member for moving said arm; means including a reversing clutch on said main drive shaft for rotating said feed screw in opposite directions; trip means including a compression spring engageable with said traveling member at the bottom of its movement for throwing said feed screw clutch to reverse the rotation of said feed screw.

23. In a device of the class described: a work supporting table; means including a clutch for rotating said table; a main drive shaft for driving said table clutch; bearing means supporting said

- main drive shaft; an upright guide member adjacent said table; a traveling arm having a portion thereof engaged in said guide member and an extending portion projecting above said table; 5 an upright feed screw mounted adjacent said guide member; bearing means supporting said feed screw; a traveling member on said feed screw; means engaged by said traveling member for moving said arm; means including a reversing clutch on said main drive shaft for rotating said feed screw in opposite directions; means including a yieldable member for engaging said table clutch; latch means associated with said table for holding said table clutch in disengagement against the action of said yieldable means; a trip bar adjacent said feed screw; a stop on said trip bar engageable by said traveling member at the bottom of its movement; means operable by the downward movement of said trip bar to throw said feed screw clutch into a reverse position; another stop on said trip bar engageable by said traveling member at the top of its stroke; 10 means operable by the upward movement of said trip bar to disengage said feed screw clutch and release said latch, thereby permitting the engagement of said table clutch and the rotation of said table; and means including a cam member on 15 said table and a lever member in said trip mechanism for disengaging said table clutch and re-engaging said feed screw clutch.
- 20 25. The method of treating brake drums and the like, which includes: subjecting the wearing surface thereof to the action of a hot metal spray; rotating said drum during such spraying action; and effecting a gradual reciprocating axial movement between said drum and said spray during the rotation of said drum so as to build up a 25 matted hard metal coating in said drum.
26. The method of treating a brake-drum which comprises subjecting the wearing surface thereof to the action of a spray of molten metal particles, rotating said drum during such spray- 30 ing action, and effecting a progressive relative axial movement between said drum and said spray during the rotation of said drum, said axial movement for each rotation of said drum being substantially less than the width of the area 35 covered by said spray, whereby there is built up on the wearing surface a coating of hardening material in overlapping layers, forming a covering of minute metal particles bonded to one another and to the brake drum to form a matted 40 coating on said surface.
24. In a device of the class described: a work supporting table; means including a clutch for 30 rotating said table; a main drive shaft for driving said table clutch; bearing means supporting said main drive shaft; an upright guide member adjacent said table; a traveling arm having a portion thereof engaged in said guide member and an extending portion projecting above said table; 35 an upright feed screw mounted adjacent said guide member; bearing means supporting said feed screw; a traveling member on said feed screw; means engaged by said traveling member for moving said arm; means including a reversing clutch on said main drive shaft for rotating said feed screw in opposite directions; means including a yieldable member for engaging said

PURLING A. BLEAKLEY.
